Primary Examiner — Philip S Hyder*(74) Attorney, Agent, or Firm* — Goodhue, Coleman & Owens, P.C.(57) **CLAIM**

The ornamental design for an automatic knife, as shown and described.

DESCRIPTION

FIG. 1 is a perspective view of an automatic knife showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a back view thereof.

The broken lines in the Figures show portions of the automatic knife which form no part of the claimed design.
